FIRE DIRECTOR

Joseph W. Allen, East Orange, N. J., assignor to
Bendix Aviation Corporation, South Bend, Ind.,
a corporation of Delaware

Application May 1, 1941, Serial No. 391,440

1 Claim. (Cl. 192—02)

This invention relates to fire control, and more particularly to a means for directing the fire of a flexibly mounted aircraft weapon.

Heretofore, aircraft weapons, such as machine guns, have been flexibly mounted so that the gunner might manually bring the gun to bear upon a relatively moving target in combat, or motor means have been provided to permit more facile maneuvering of the gun in the air-stream of a fast moving craft under control of the gunner, but the motor controls have had torque transmitting characteristics unsuited to the best control of the weapon's fire.

It is an object of the present invention to provide a power operated gun director having a variable torque under the control of an operator.

Other objects of the invention include the provision of a means for directing a gun in a plurality of planes at a speed regulated by the gunner, and the provision of a power control for a gun having directional and speed characteristics variable under the control of the gunner.

Other objects will appear from a study of the following specification when made in conjunction with the attached drawing, throughout which like numerals designate like parts.

Fig. 1 is a schematic diagram of one embodiment of the present invention, and

Fig. 2 is a view, in perspective, of one form of gunner's control unit adapted for use in the diagram of Fig. 1.

In accordance with the present invention, a power operated gun director is utilized for swinging a flexibly mounted gun in train and in elevation under the control of a gunner, by means of an operating mechanism comprising a universally mounted control stick, the movement of which can be made to regulate the direction of rotation of the gun and the speed with which the rotation is effected. The speed or torque characteristics of the gun director are selected by the gunner through a variable torque clutch for controlling the torque transmitted to each of the axes of rotation of the gun.

In Fig. 1, 10 represents a flexibly mounted machine gun having a pedestal member 11 mounted on a base member 12, to which is affixed an annular beveled gear 13. The gun 10 may be rotated with respect to pedestal 11 about a horizontal or elevational axis 14 and the gun and pedestal may be rotated as a unit about a vertical or train axis 15. A beveled pinion 16 carried on a splined shaft 17 meshes with beveled gear 13. Shaft 17 has a core portion 18 of soft iron or other magnetizable material, to which is attached

a section 19 of brass or other non-magnetizable material carrying one plate 20 of a clutch 21. A shaft 22 carries a second clutch plate 23 and is rotatable under control of a motor 24.

5 Motor 24 may be of the series-wound, D. C. type having an armature 25 and two oppositely wound field members 26 and 27. Motor 24 may be energized by means of a battery 28 which is connected thereto through a lead 29, a conductor 30 and either of conductors 31, 32, by way of relay members 34 and 35. Relay members 34 and 35 have solenoids 36 and 37, respectively, which may be placed in circuit with battery 28 in the manner stated below.

Upon the movement of contact arm 38 to engage with contact strip 39, current flows through conductor 30, branch lead 40, solenoid 36, conductor 41, contact strip 39, contact arm 38 and back to the battery through leads 42 and 29. When current flows in this circuit, the armature 43 of relay 34 is attracted outwardly from its open or de-energized position, thereby permitting current to flow through field 26 of motor 24, causing rotation of shaft 22 in one direction. If contact arm 38 is moved into engagement with contact strip 44, relay 34 becomes de-energized, opening the circuit of field 26, but current now flows from battery 28 through conductor 30, branch lead 45, solenoid 37, conductor 46, contact strip 44, contact arm 38 and back to the battery through leads 42 and 29. When current flows through solenoid 37, armature 47 of relay 35 is attracted downwardly, thus closing the motor circuit which includes field 27. This results in rotation of shaft 22 in a direction opposite to that caused by energization of field 26.

By means of similar circuits, motor 24' may be energized to rotate in either direction and drive gun 10 in elevation through a clutch 21' and a worm and gear 48.

Current from battery 28 is available to the motor and relay circuits for driving gun 10 in elevation through conductors 49 and 50, which connect one side of battery 28 to relays 34' and 35' (similar to relays 34 and 35, respectively) through parallel branch leads 40' and 45'. The other side of battery 28 is connected to the armature (not shown) of motor 24, through leads 29, 42, jumper 51 and conductor 52.

Movement of contact arm 38' into engagement with contact strip 39' actuates relay 34' as the battery circuit becomes completed through lead 41'. Actuation of relay 34' energizes motor 24' through one of oppositely wound fields (not

shown), similar to the fields 26 and 27 of motor 24.

When contact arm 38' is moved into engagement with contact strip 44', the battery circuit for actuating relay 35' is closed through conductor 46'. Actuation of relay 35' inserts a second field member (not shown) into the motor circuit to drive motor 24' in a direction opposite to that in which it is driven upon actuation of relay 34'. The motor 24', relays 34' and 35', and the associated leads for energizing motor 24', being all similar to the motor 24, relays 34 and 35 and the associated leads, respectively, the identical members forming the circuit of motor 24' have been designated by the same numerals as were used in the description of the circuit of motor 24, with the addition of primes for those elements used in the circuit of motor 24'.

Movement of contact arm 38 into engagement with contact strip 39, also connects resistor 53 into a circuit including connector 54, lead 55, coil 56, conductors 57, 58, 49 and battery 28. Coil 56 is a stationary solenoid wound about the magnetizable core member 18, and when current flows through coil 56, it draws core member 18 to the right, to press clutch plate 20 into engagement with plate 23. When contact arm 38 is moved only slightly in a counter-clockwise direction, the current from battery 28 must flow through the entire resistor 53, and therefore, the current flowing through coil 56 is small, and therefore, core 18 exerts only a slight pressure of plate 20 against plate 23. In this condition, the torque transmitted from shaft 22 to splined shaft 17 is low, resulting in quite a bit of slippage between clutch plates 20 and 23. The resultant rotation of gun 10 about the vertical axis 15 is at a slow rate. When contact arm 38 is moved counter-clockwise to its extreme right-hand position, with resistor 53 completely out of the battery circuit, the maximum current flows from battery 28 through coil 56, and core 18 presses plate 20 into engagement with plate 23 with maximum pressure, and the clutch plates are closely coupled, that is, the relative rotation between the clutch plates 20 and 23, is a minimum or zero, and gun 10 is consequently rotated about axis 15 at its maximum speed. Shaft 17 is splined so that lateral movement of core 18 does not affect the engagement of pinion 16 with beveled gear 13.

Movement of contact arm 38 clockwise from its neutral position, as shown, results in the insertion of a resistor 59 in circuit with coil 56 and battery 28. For reasons above explained, when the maximum resistance of resistor 59 is in circuit with battery 28, then core 18 urges plate 20 into engagement with plate 23 with minimum pressure, and the torque transmitted to splined shaft 17 is a minimum. This is the condition that obtains when contact arm 38 is moved only slightly clockwise from its neutral position. When contact arm 38 is moved to its maximum clockwise position, all of resistor 59 is removed from the battery circuit, and the current through coil 56, being at a maximum, will attract core 18 with maximum force, and thus, clutch plates 20 and 23 will be coupled so closely that the torque transmitted to shaft 17 is a maximum, and gun 10 is thus rotated in train at its greatest speed.

Between the minimum and maximum conditions of torque transmission, varying amounts of torque may be transmitted from shaft 22 to shaft 17, depending upon the amount of resistance of either resistor 53, or resistor 59, that is left in circuit with battery 28. As the amount of

resistance in the circuit depends upon the amount of movement of contact arm 38 from its neutral position, it will be seen that the torque transmitted from motor 24 to gun 10 in the train axis depends upon the amount of movement of contact arm 38 from its neutral position.

As the circuits associated with contact arm 38' for delivering variable torque to worm and gear 48 are identical to the variable torque circuits just described, and since the identical components of the circuits connected with contact arm 38' are designated by prime equivalents of the same components associated with contact arm 38, it is believed that the operation of the variable torque supplying means for driving gun 10 about the horizontal or elevational axis 14 will be clear without further description.

Fig. 2 shows a universally mounted control column 60, which is operated by a gunner to direct the fire of gun 10 in elevation and train, either separately or simultaneously, at varying speeds. Control column 60 is shown in its neutral position; that is, gun 10 is at rest. Control column 60 is connected by means of trunnions 61 to a ring member 62, and has suitable bearings (not shown), so that trunnions 61 may be oscillated about their axis with respect to ring 62 upon motion of column 60. At right angles to trunnions 61, ring 62 is borne on two co-axial shaft members, 63 and 64, which are rigidly connected to ring 62. One end of shaft 64 is carried in a suitable bearing member such as the ball-bearing and race member 65. Member 65 is carried by a wall of housing member 66, which may be of cast metal or molded plastic material. The outer end of shaft 63 carries contact arm 38, so that motion of control column 60, to rotate shaft 63, will cause contact arm 38 to engage with contact strip 39 and resistor 53, or contact strip 44 and resistor 59.

Housing 66 also carries co-axial shaft members 67 and 68 at right angles to shaft members 63 and 64. The outer end of shaft 67 is connected to contact arm 38', while the other end is rigidly connected to one end of a slotted yoke member 69. The outer end of shaft 68 is carried in a ball-bearing member 70 fixed to a wall of housing 66, and the inner end of shaft 68 is rigidly connected to the opposite end of yoke member 69. The arcuate slot 71 in yoke member 69 has just sufficient width to permit control column 60 to slide therealong without excessive clearance. Motion of control column 60 to rotate yoke 69 and shaft 67 will cause contact arm 38' to be moved into engagement with contact strip 39' and resistor 53', or contact strip 44' and resistor 59'.

It will be readily appreciated that when control column 60 is moved only in a plane at right angles to shaft 63, there will be no rotation of shaft 67, and when column 60 is rotated only in a plane at right angles to shaft 67, no rotation will be imparted to shaft 63. When, however, column 60 has a component of motion in each of these planes, then components of the total motion will cause rotation of shaft 63 and shaft 67. When only shaft 63 is rotated, gun 10 is rotated only in train. When shaft 67 alone is rotated, gun 10 is rotated only in elevation. When both of shafts 63 and 67 are rotated, gun 10 will have motion both in train and in elevation.

It will be understood from the preceding description that the direction of rotation of gun 10 about either the train or the elevational axis, 75 is governed by the direction of movement of

column 60, and the speed of rotation of gun 10 about these axes is governed by the amount of movement of column 60 from neutral, so that a gunner may bring gun 10 to bear upon its target either slowly or quickly, depending upon combat requirements. If desired, a button 12, for actuation of the conventional trigger relay, may be incorporated into hand grip 13 of control column 60.

While only one embodiment of the present invention has been shown in the drawing, it is to be understood that various changes may be made without departing from the scope of the present invention. For this reason, it is intended not to limit the invention by the description herein given as an example, but solely by the scope of the appended claim.

I claim:

A power control system including a first reversible motor, a second reversible motor, a con-

10 trol column, means actuated by said control column and in circuit with each of said motors for selecting the direction of rotation of said motors in accordance with the direction of movement of said control column, electromagnetic clutch means in circuit with said motors and actuated by said control column, and continuously variable resistance means in circuit with said control column and said electromagnetic clutch means to transmit currents to said electromagnetic clutch means varying in accordance with the amount of movement of said control column from a determined neutral position, whereby the torque transmitted to each of said motors through said electromagnetic clutch means will vary in accordance with the amount of movement of said control column from the neutral position.
